(57) CLAIM

The ornamental design for a glove, as shown and described.

DESCRIPTION

FIG. 1 is a bottom plan view of the glove;

FIG. 2 is a left side elevational view of the glove;

FIG. 3 is a right side elevational view of the glove;

FIG. 4 is a top plan view of the glove; and,

FIG. 5 is a front elevational view of the glove.

The broken lines shown on the glove are included for the purpose of illustration and form no part of the claimed design.
